CLAIM

The ornamental design for a tool bag as shown and described.

DESCRIPTION

FIG. 1 is a back perspective view of the tool bag as worn during use;

FIG. 2 is a front view of the tool bag as worn during use; FIG. 3 is a bottom view of the tool bag as worn during use; FIG. 4 is a left side view of the tool bag as worn during use; FIG. 5 is a right side view of the tool bag as worn during use; FIG. 6 is another front perspective view of the tool bag as worn during use;

FIG. 7 is a detailed view of one of the tool pouches to be used with the tool bag; and,

FIG. 8 is a detailed view of the other of the tool pouches to be used with the tool bag.

The broken lines showing the suspender and belt for wearing the tool bag form no part of the claimed design but depict the environment of the claimed design. The broken lines showing the stiches of tool bags form no part of the claimed design.

1 Claim, 8 Drawing Sheets
